Primary Examiner — Mehri F Bajoul(74) *Attorney, Agent, or Firm* — Heslin Rothenberg Farley & Mesiti P.C.(57) **CLAIM**

The ornamental design for game target, as shown and described.

DESCRIPTION

FIG. 1 is a perspective view of game target comprising the new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken lines shown in the drawings depict portions of the game target that form no part of the claimed design.
